UNITED STATES PATENT OFFICE

147,644

DESIGN FOR A SLED EQUIPPED TANK FOR VACUUM CLEANERS

Robert S. Flannigan, Skaneateles, N. Y.

Application July 23, 1946, Serial No. 131,857

Term of patent 3½ years

(Cl. D9—2)

To all whom it may concern:

Be it known that I, Robert S. Flannigan, a citizen of the United States, residing at Skaneateles, in the county of Onondaga and State of New York, have invented a new, original, and ornamental Design for a Sled Equipped Tank for Vacuum Cleaners, of which the following is a specification, reference being had to the accompanying drawing, forming part thereof.

Figure 1 is a side elevational view of a sled equipped tank for vacuum cleaners, showing my new design.

Figure 2 is an end view of same observing Figure 1 in a direction from left to right.

Figure 3 is an end elevation of the opposite

end of observing Figure 1 in a direction from right to left.

I claim:

The ornamental design for a sled equipped tank for vacuum cleaners, as shown.

ROBERT S. FLANNIGAN.
